UNITED STATES PATENT OFFICE.

EMILE DOR DELATTRE, OF LIEGE, BELGIUM.

APPARATUS FOR OBTAINING INTIMATE MIXTURES.

No. 922,863.

Specification of Letters Patent.

Patented May 25, 1909.

Application filed November 15, 1907. Serial No. 402,362.

To all whom it may concern:

Be it known that I, EMILE DOR-DELATTRE, a resident of Liege, Belgium, a subject of the King of the Belgians, engineer, have invented certain new and useful Improvements in Apparatus for Obtaining Intimate Mixtures, of which the following is a full, clear, and exact description, such as will enable others skilled in the art to which it appertains to make and use the same.

The present invention relates to an apparatus for mixing materials and has for its object to provide means by which materials of different character or of different degrees of fineness may be thoroughly mixed.

In the accompanying drawing, Figure 1 is a front view of an apparatus constructed in accordance with the invention; Fig. 2 is a side view of the apparatus; and Fig. 3 is a horizontal section on the line A—B of Fig. 1.

Referring to the drawings, the embodiment of the invention illustrated includes two similar receptacles 1, 2, each interiorly divided into a plurality of vertical compartments open at both ends.

Above the receptacles is arranged a horizontal screw conveyer 3 of such length as to extend entirely across both receptacles, said conveyer working within a suitable casing 4, open at its top, and being adapted, by suitable clutch devices not shown, to rotate in either direction. Below each receptacle is arranged a belt conveyer 5, 6, adapted to deliver material received thereon to a screw conveyer 8. The section of the conveyer 8 coöperating with the belt 5 is the reverse of the section thereof below the belt 6 so that material delivered to said screw by either of the belt conveyers will be carried to an elevator 7 arranged between the receptacles 1, 2.

The elevator 7 is provided at its upper end with a discharge chute 17 which extends across the top of the casing of the feed screw 3, and a valve 9 mounted to turn about an axis 16 is arranged in said chute. By adjusting this valve the elevator can be caused to discharge either into the casing 4 of the feed screw 3 or through the chute 17.

The manner of using the apparatus may be briefly stated as follows: The materials to be mixed are successively delivered to the lower leg of the elevator 7 or to the conveyer 8 and the valve 9 is adjusted into position to extend across the discharge chute. Power being supplied to the elevator and feed

screw 3, and the latter rotated to convey material through the casing 4 over the receptacle 1, the compartments 11, 12, 13, 14 and 15 of said receptacle will be successively filled. When the receptacle 1 is completely filled or the desired amount of material deposited therein, the supply of material is cut off; and thereafter the conveyers 5 and 8 are started and the direction of movement of the feeding screw 3 reversed. The conveyer 5 operates to remove the material from the receptacle 1, each of the compartments in said receptacle simultaneously discharging upon the conveyer and thereby the several substances previously contained in said receptacle will be primarily mixed as they are delivered to the screw conveyer 8. By this conveyer and the elevator 7 the partially mixed materials will be discharged into the casing 4 and by the feed screw 3 deposited in the receptacle 2, the compartments 21, 22, 23, 24 and 25 of said receptacle being successively filled.

When the belt conveyer 6 is set in motion the materials contained in the receptacle 2 will be withdrawn and if a further mixing is not desired the valve 9 will be adjusted to cause the elevator to discharge through the chute 17. However if the valve 9 is left in position to cause the elevator to discharge its load on to the feed screw 3, and the direction of movement of said screw is again reversed, the materials which have been mixed by the action of the conveyers 5 and 6 will be returned to the receptacle 1 and again mixed as they are withdrawn from such receptacle by the conveyer 5. By repeating the operations above described it is possible to obtain a very intimate mixture of a variety of substances, it being understood of course that in the initial operation the several compartments of the receptacle 1 are filled with different materials or material of different grades of fineness, etc.

No claim is herein made to the novel process or method of mixing described as the same forms the subject-matter of a separate application, Serial No. 402,361.

Having thus described the invention what is claimed is:

1. An apparatus for the purpose described comprising two receptacles, a conveyer traveling beneath each receptacle, an elevator adapted to receive material from both conveyers and to carry the same to points above the receptacles, means for transport-

- ing material delivered by the elevator to either of the receptacles, a discharge chute arranged to receive material from the elevator, and a controlling device by which material discharged by the elevator is delivered to either said transporting means or chute.
2. An apparatus for the purpose described comprising two receptacles, means for conveying material from the lower end of either receptacle to the upper end of the other including a reversible conveyer adapted to deliver material to one receptacle when moving in one direction and to the other receptacle when moving in the opposite direction.
3. An apparatus for the purpose described comprising two receptacles, a reversible feeding device adapted when moving in one direction to deliver material to one receptacle and to deliver material to the other receptacle when moving in the opposite direction, independent conveyers each adapted to receive material from one of the receptacles, an elevator adapted to deliver material to the feeding device, and means for transporting material from both said conveyers to the elevator.
4. An apparatus for mixing substances, comprising two receptacles having vertical compartments, a reversible screw conveyer for feeding the substances to either of said receptacles, means for emptying said receptacles by horizontal layers, an elevator delivering to said screw conveyer, and means for transporting the material of said layers to said elevator.
5. An apparatus for mixing substances, comprising two receptacles having vertical compartments, means for feeding the substances to the successive compartments of either receptacle, means for emptying said receptacles by horizontal layers, and means for conveying the material of said horizontal layers to said feeding means.
6. An apparatus for mixing substances, comprising two receptacles having vertical compartments, a reversible screw conveyer feeding the substances to the successive compartments of either receptacle, transporters emptying said receptacles by horizontal layers, a double screw conveyer receiving from said transporters, and an elevator fed
- by said double screw conveyer and delivering to said reversible screw conveyer.
7. An apparatus for mixing substances, comprising two receptacles having vertical compartments, a reversible screw conveyer feeding the substances to the successive compartments of either receptacle, alternately operating transporters emptying said receptacles in turn by horizontal layers, a double screw conveyer receiving from one of said transporters, an elevator fed by said double screw conveyer, said elevator normally delivering to said reversible screw conveyer, and a pivoted trap movable into the line of delivery of said elevator.
8. An apparatus for the purpose described, comprising two receptacles each having its interior divided into a plurality of vertical compartments, a conveyer traveling beneath each receptacle and adapted to simultaneously receive material from all of the compartments thereof, an elevator adapted to receive material from both said conveyers, and deliver the same above the receptacles, means for transporting material delivered by the elevator to the several compartments of one receptacle successively when operated in one direction, and similarly to the other receptacle when operated in a different direction, and means for causing said elevator to deliver the material at a point outside of both said receptacles.
9. An apparatus for the purpose described, comprising two receptacles each having its interior divided into a plurality of vertical compartments, a conveyer traveling beneath each receptacle and adapted to simultaneously receive material from all of the compartments thereof, an elevator adapted to receive material from both said conveyers, means for receiving material from said conveyer and discharging the same into the compartments of either receptacle and means for causing the elevator to discharge its contents at a point outside of either of said receptacles.
- In testimony whereof I have signed my name to this specification in the presence of two subscribing witnesses.
